UNITED STATES PATENT OFFICE.

ALEXANDER A. WHITELY AND WILLIAM A. DUNCAN, OF NEW YORK, N. Y.,
ASSIGNORS TO MAUDE I. WHITELY, OF SAME PLACE.

PUNCHING-BAG EXERCISER.

SPECIFICATION forming part of Letters Patent No. 663,690, dated December 11, 1900.

Application filed February 19, 1900. Serial No. 5,681. (No model.)

To all whom it may concern:

Be it known that we, ALEXANDER A. WHITELY, a resident of the city of New York, borough of Manhattan, New York county, and WILLIAM A. DUNCAN, a resident of New York, (Long Island City,) Queens county, State of New York, citizens of the United States, have invented certain new and useful Improvements in Punching-Bag Exercisers, of which the following is a specification.

Our invention relates to punching-bag exercisers, and has for its object to provide a simple and efficient means of attaching or securing a punching-bag to a standard and so that the bag may be readily attached to and detached from such standard.

To this end the invention consists in the novel details of improvement and the combination of parts hereinafter described and claimed.

Reference is to be had to the accompanying drawings, forming part hereof, in which—

Figure 1 is a longitudinal cross-section of the punching-bag and head portion of the standard on the line 33 of Fig. 2. Fig. 2 is a sectional view of the bag fastened over the head of the standard, the section being taken on the line 44 of Fig. 1; and Fig. 3 is a detail view, partly in cross-section, of the standard and its head.

In the drawings, A indicates the standard, at one end of which is a head or top piece G, whose base is slightly concave and whose other side is of convex or rounded shape, as shown; but the shape of the head G may be varied, if desired.

H indicates the usual bladder or inner portion of a punching-bag and is adapted to be inflated through the medium of the valve-stem i.

B indicates the outer or enveloping covering of the inner bag H. This enveloping cover B is preferably made of leather and is open or slitted at j for a portion of its circumference, so as to permit of the insertion of the head G of the standard, the edges of the slitted portion of the outer bag or covering B being adapted to be laced over or around the head G by lacing k; but other means may be employed for drawing together the edges of the slit portion of the outer bag B over the head G. In the head G we provide an opening or aperture l, through which the valve-stem i of the inflatable bag may be passed.

To attach the bag to the standard, the head G is inserted through the opening or slit j of the outer bag B and the valve-stem i of the inner bag H inserted through the aperture l in the head G. The edges of the opening in the enveloping cover B are thereupon laced together or otherwise fastened over the head. As the inner bag or bladder H is inflated and expanded it will press against the base of the head G and expand with it the outer bag or covering B, and the greater the expansion the more firmly will the outer bag B press upon and grasp the head portion G of the standard, the inner bag H at the same time also bearing with greater pressure upon the face of the head G, and thus the outer covering B is effectively held over and around the head G. In this manner we produce a simple and efficient means of attaching the bag to the standard, at the same time permitting the bag to be readily detached therefrom.

We do not limit the invention to the precise details shown and described, as they may be varied without departing from the spirit of our invention.

What we claim, and desire to secure by Letters Patent, is—

1. The combination of a standard having a head, with an inflatable bag and an enveloping covering substantially surrounding the bag and the said head, the enveloping covering having an opening through which the head and bag can be passed with means for detachably securing the covering over said head, the head being provided with an opening and the inflatable bag having a valve-stem passing through said opening, substantially as described.

2. The combination of a standard having a head portion, with an inflatable bag, and an enveloping covering having an opening, through which the head and the bag can be passed, said enveloping covering substantially surrounding the inflatable bag and the said head, with means for detachably securing the edges of the opening of the enveloping covering together across the outer part of the head transversely of the latter.

ALEXANDER A. WHITELY.
WILLIAM A. DUNCAN.
